UNITED STATES PATENT OFFICE.

JOHN D. PLANCHAMP, OF CHICAGO, ILLINOIS.

JEWELER'S STOCK-PLATE.

SPECIFICATION forming part of Letters Patent No. 426,059, dated April 22, 1890.

Application filed August 12, 1889. Serial No. 320,525. (No model.)

To all whom it may concern:

Be it known that I, JOHN D. PLANCHAMP, a citizen of the United States, residing at Chicago, in the county of Cook and State of Illinois, have invented certain new and useful improvements in Jewelers' Stock-Plate, which are fully set forth in the following specification, reference being had to the accompanying drawings, forming a part hereof, and in 10 which—

Figure 1 shows my jeweler's stock-plate in sectional elevation. Fig. 2 shows the same in plan.

Like letters of reference denote like parts. 15 The object of my invention is to construct an improved stock - plate for watch - case makers, jewelers, and like arts, in which varieties of forms and colors on the same plate may be displayed for the purpose of produc-

20 ing new and useful results, which I attain in substantially the following manner, namely:

I solder together on their edges plates of the desired metals of various colors, as shown in Figs. 1 and 2, in which the parts 1 2 3 4 represent different pieces of metal, as gold, silver, oxidized silver, and oxidized gold, and again, and preferably, the said parts may consist of gold of various shades of colors—such as can now be produced in the arts—and when 25 said plates are soldered together at their edges they are rolled into plates of such desired thickness and area as may be required for the construction of an object—as, for instance, a watch-case.

30 A watch-case thus made will show varieties of metal and color in bands or spots, as the result may be, depending on the manner in which the stock-plate was formed, and such bands or spots will appear in substantially

equal area and like forms in outline on both 40 sides of the plate or case, which through said construction also shows that the metal is of the same nature from one side to the other of the watch-case. If, however, it is desired to make what is termed a "filled" case, I lay the 45 said variegated plate upon the composition or base metal *a* intended to be used for the filling and roll the said parts together until they are of the required thickness and area, and then shape it, as before, into the desired 50 object. In the last instance the said base metal would form the interior of the watch-case; but this may also be covered by a lighter covering of plate *c*, soldered to the filling and rolled out, and this interior plate may also be composed of patches of various colors of metal constructed in the same manner as the outside of the case. 55

It is evident that the same varieties of metal of various colors may be produced in 60 every other variety of jewelry in substantially the same manner.

What I claim is—

1. The art or process of manufacturing jewelers' party-colored stock-plate, which consists 65 in uniting metals of various colors and forms on their horizontal edges only, so as to form a plate, and then rolling the same into sheets, substantially as specified.

2. A jeweler's stock-plate which consists of 70 metals of various colors and united at their horizontal edges only for the purpose of ornamentation on both sides of the plate, substantially as specified.

JOHN D. PLANCHAMP.
